CLAIM

The ornamental design for an apertured hollow wand for blowing water off surfaces, as shown and described.

DESCRIPTION

FIG. 1 is a side view of an apertured hollow wand for blowing water off surfaces showing my new design and shown in operative association with a blower and automobile, both shown in phantom outline and not part of the present invention;

FIG. 2 is an enlarged perspective side and bottom view thereof;

FIG. 3 is an end view thereof, taken from the left of FIG. 1; FIG. 4 is a sectional view thereof taken in the direction of the arrows upon the line 4—4 of FIG. 4; and,

FIG. 5 is a bottom view thereof.
